(57) **CLAIM**

The ornamental design for a bottle closure, as shown and described.

DESCRIPTION

FIG. 1 is a first perspective view of a bottle closure showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a second perspective view thereof;

FIG. 9 is a third perspective view thereof;

FIG. 10 is a cross-sectional view thereof taken along line 10-10 of FIG. 7; and,

FIG. 11 is a cross-sectional view thereof taken along line 11-11 of FIG. 7 (the view in the opposite direction of the line 11-11 is a mirror image thereof).

The broken lines immediately adjacent the shaded areas depict portions of the bottle closure that are not included in the claim. The oblique broken lines depict portions of the interior of the bottle closure in FIGS. 10 and 11 that form no part of the claimed design. All other broken lines illustrate the environment of the outer profile and interior of a bottle that forms no part of the claimed design.
